UNITED STATES PATENT OFFICE.

THOMAS CARTER, OF BELTON, SOUTH CAROLINA, ASSIGNOR, BY DIRECT AND MESNE ASSIGNMENTS, TO DRAPER CORPORATION, OF HOPEDALE, MASSACHUSETTS, A CORPORATION OF MAINE.

FILLING-END FINDER AND FILLING-CARRIER FEEDER.

1,277,376.

Specification of Letters Patent.

Patented Sept. 3, 1918.

Application filed March 28, 1916. Serial No. 87,358.

To all whom it may concern:

Be it known that I, THOMAS CARTER, a citizen of the United States, residing at Belton, in the county of Anderson and State of South Carolina, have invented new and useful Improvements in Filling-End Finders and Filling-Carrier Feeders, of which the following is a specification.

This invention relates to a filling end finder and filling carrier or bobbin feeder for use in finding and extending the ends of the filling threads wound upon the carriers and feeding the carriers to a battery or magazine, so that the carriers will be fed up to the weaver or a battery ready for a loom replenishing action with the ends of the fillings in position to be laid in the shed on the first picks of the shuttles following the transfer of the carriers thereto.

In the preparation of yarn for use as filling in the weaving of cloth, the spun yarn is wound upon a carrier or bobbin and the loose end of the yarn or filling is temporarily secured, ordinarily by giving it a loose or coarse wind about the body of the filling, so that when the carrier is to be used the weaver may find and unwind the loose end of the thread and extend the same for transfer to the shuttle or to the battery preliminary to transfer to the shuttle. All of these operations are customarily performed by hand, the weaver taking the filling carrier from a box or receptacle in which it is contained with others and then unwinding the loose end of the filling and placing the carrier in the shuttle or battery as the case may be, according to the character of the loom, whether hand or automatically fed for the replenishing action. These operations are tedious and consume much time and cause a great deal of trouble to the weaver, as the filling end clings closely to the body of the filling and is therefore difficult to find and remove for the purpose of extending or leading the filling from the tip end of the carrier.

The primary object of the present invention is to provide a machine or apparatus by means of which the filling ends may be readily found and unwound and properly presented for the transferring or replenishing action; and a further object of the invention is to provide a machine or apparatus whereby the carriers or bobbins may

also be fed to the battery and the leading ends of the threads secured in extended position, so that the filling will be properly presented either for a shuttle threading or automatic filling replenishing action.

With these and other objects in view, the invention consists of the features of construction, combination and arrangement of parts hereinafter fully described and claimed, reference being had to the accompanying drawings, in which:

Fig. 1 is a front elevation of a filling end finder and filling carrier feeder embodying my invention, and showing the parts as they appear just prior to the release and return of the carriage after one operation and the feeding up of a filler carrier for the next operation.

Fig. 2 is a view in elevation of the same looking toward the side of the machine at which the main drive gearing is arranged.

Fig. 3 is a view in elevation looking toward the opposite side of the machine.

Fig. 4 is a sectional plan view on the line 4—4 of Fig. 2.

Fig. 5 is a vertical front to rear section on line 5—5 of Fig. 1.

Fig. 6 is a detail section on the line 6—6 of Fig. 1, illustrating the action of the thread end winding hook.

Fig. 7 is a sectional plan view on an enlarged scale showing the finder finger in position acting upon a carrier for the finding action.

Fig. 8 is a vertical section on line 8—8 of Fig. 7.

Fig. 9 is a similar view showing the thread end found and caught up by the finder finger.

Fig. 10 is a section on line 10—10 of Fig. 7, showing the finger in the position illustrated in Fig. 9.

Fig. 11 is a cross section on the line 11—11 of Fig. 10.

Fig. 12 is a detail section on line 12—12 of Fig. 9.

Fig. 13 is a fragmentary top plan view of the outer end of the horizontal guide frame, showing the latch device for holding the carriage during the action of the winder hook.

Fig. 14 is a section on line 14—14 of Fig. 13, showing the latch in engagement with the carriage.

Fig. 15 is a detail section on line 15—15 of Fig. 2.

Fig. 16 is a view illustrating a slight modification of the finder finger.

5 In the practical embodiment of my invention, I provide a suitable construction of frame including a hopper 1 and a front horizontal guide frame portion or track 2. The hopper 1 is in the form of a box or 10 receptacle designed to receive and contain the filling carriers or bobbins 3 which may be filled therein by hand or by means of any suitable conveying mechanism. This hopper is provided at its lower front portion 15 with a feed outlet or passage 4 controlled by a swinging valve or gate 5 mounted at its upper end upon a horizontal transverse shaft 6 provided at one end with an adjustable trip arm 7. The other end of the shaft 20 6 is provided with a lever arm 8 which is connected with a coiled contractile spring 9 operating to normally hold the gate closed, a stop 10 being provided for engagement by the lever 8 to limit the closing movement of 25 the gate. The filling carriers or bobbins 3 contained within the hopper rest upon and are supported by the upper stretch of an endless feed belt or apron 11, which forms the bottom of the hopper and by means of 30 35 which the carriers are individually fed to the outlet 4 for discharge. On the forward motion of the upper stretch of the belt, and at a proper time period, the gate 5 is swung outwardly to allow the foremost carrier to 40 pass through the outlet 4, the gate then closing to hold the remainder of the carriers from discharge. The belt passes around front and rear shafts 12 and 13, and upon one end of the rear shaft is fixed a 45 pinion 14 through which forward feed and rearward agitating motions may be transmitted to the belt as hereinafter described. Disposed immediately above the forward edge of the belt is a guard roller 15 which 50 extends transversely of the hopper, at a sufficient distance above the belt to provide a throat of proper depth for the passage of a single carrier or bobbin at a time, by which the passage of more than a single bobbin at 55 any one time will be prevented. The ends of this roller are mounted for rotation and vertical motion to a limited extent in bearing slots 16 formed in the side walls of the hopper, so that in the event of a second 60 carrier being caught at an angle in the throat between the roller and a discharging carrier the roller may yield upward to prevent binding of the carriers in the outlet, and so that on the reverse or backward 65 movement of the belt the carrier first mentioned will be moved back and the carriers straightened out and loosened up in order that they may properly assume their positions by gravity without binding or hanging in the hopper. By this means any tend-

ency of the carriers to clog the hopper will be prevented and a certainty of feed action of the carriers obtained.

Each carrier or bobbin 3 discharged through the outlet 4 drops by gravity into 70 a movable supporting frame comprising in the present instance a horizontal transverse bar 17 carried by the lower ends of vertical arms 18 pivotally mounted at the sides of the hopper, as indicated at 19, to adapt the 75 U-shaped frame thus formed to swing in a direction toward and from the outlet. The swinging frame is normally maintained in a forward operative position by means of a coiled retracting spring 20, and upon the bar 17 of the frame are forwardly extending bearing brackets 21 in which are journaled the ends of a roll 22 upon which the carrier or bobbin discharged for the finding action rests and whereby such bobbin or carrier is turned or rotated during the finding action, said roll carrying at one end a gear pinion 23 whereby it is revolved as hereinafter described. The filling carrier or bobbin which is supported by the 90 roll 22 is centered and maintained in position during the finding action by a U-shaped holder or guide 24, supported by the frame or track 2, and which loosely receives the butt end of the bobbin, the tip end of which 95 comes between a bracket piece or stop member 25 on the frame 3 and a similar bracket piece or stop member 26 on the bar 17 by which such end of the bobbin is held against other than a limited back-and-forth movement, the centering devices, however, permitting the carrier or bobbin to freely drop down into position and to be freely revolved. 100

The means for finding the lead end 27 of the filling 28 upon the bobbin 3 which is 105 being supported and rotated by the roll 22 consists of a finder finger 29 which is in the form of a thin blade disposed edgewise in a vertical position and provided at one end with a shank 30 which is fitted to slide or 110 reciprocate in a backward and forward direction, or in a direction transversely to the axis of the bobbin, in a guide passage 31 formed or provided in a carriage 32, which 115 guide passage 31 is formed at its inner end with a depression or recess 33. The carriage 32 is mounted for sliding travel on rods 34 and 66 (the latter forming a rock shaft as hereinafter described) mounted on the frame portion or trackway 2 and is adapted to be 120 disposed at one point in its path of movement in position to bring the finger above and in contact with the bobbin for a finding action, as shown particularly in Figs. 7 and 8, and said carriage is provided with a slot- 125 ed extension 35 in which is arranged a stationary cutter blade 36 for co-operation with the finder finger. The finger is pivoted, as at 37, to the inner end of an actuating rod 39 arranged to reciprocate in the passage 31 130

to move the finder inwardly and outwardly to operative and retractive positions, said rod having at its outer end a head or abutment 40 and being normally held retracted by a spring 41. When the finger is moved inwardly it is permitted by the recess 33 and its pivot 37 to drop by gravity into contact with the bobbin for the finding action, as shown clearly in Fig. 8, in which position 10 the finger swings downwardly out of the slotted extension 35, while when the finger is retracted, it is elevated into said slotted extension to a normally horizontal position by the withdrawal of its shank 30 backward 15 into the passage 31, whereby the pivotal connection between the same and the rod 39 is made rigid.

The finder finger is provided with a toothed or hooked surface to engage the filling, and as shown in the present instance this toothed surface comprises a series of teeth 42 formed by curved or arcuate slots 43 extending through the lower edge of the finger and curved upwardly and forwardly, 20 so that the filler thread entering any of the slots will pass upward on and be caught by the upper inclined surface of the tooth and so held against displacement. When the finger is moved inwardly by the sliding motion of its actuating rod 39 and drops by gravity down upon the surface of the winding on the filling carrier it rides yieldingly in contact with such winding and engages and picks up the free end 27 of the thread, 25 and then upon the retraction of the finger it draws the thread end up into the slotted extension 35 so that the thread will be cut or severed by the blade 36 and thus freed from the butt end of the carrier about which 30 it is wound. The thread end will then be in position ready to be extended or carried forward beyond the tip end of the bobbin so as to be properly presented to the weaver or to a thread holder upon the battery to 35 which the carrier is conducted. The end 40 of the rod 39 is arranged in the path of movement of a pusher or presser arm 44 carried by a rock shaft 45 provided with an adjustable actuating or trip arm 46, said 40 presser arm and shaft being normally held retracted by a spring 47. When the arm 44 is moved inwardly the finger will be projected for action in an obvious manner and when said arm is released the springs 41 and 47 return the respective parts to normal 45 position.

Upon the finding or picking up of the thread from the carrier the thread is carried forward by the carriage to extend it to 50 a proper leading position and engage it with a holder, while at the same time the carrier or bobbin is released and allowed to drop into a suitable receptacle. This receptacle or holder for transfer to the shuttle is shown 55 in the present instance in the form of a bat-

tery 48, of the rotary type employed in connection with self replenishing looms, and may be rotated in practice in timed accord with the filling finding and feed mechanism to present the pockets or receptacles thereof 70 in proper position to receive the carriers as they are discharged by a rearward movement of the roller 22 at the end of the finding action. The battery may be rotated by any suitable mechanism, not necessary to be 75 shown, as the battery itself constitutes no part of the present invention, but arranged in proper position to receive the ends of the threads extending from the carriers on the battery is a thread holder 49 which may be 80 supported either from the battery or from the frame 2, as shown in the present instance. At the end of the finding action the carrier or bobbin supported by the roll 22 is dropped into the battery by retracting 85 said roll, as indicated in dotted lines in Fig. 3, which action is permitted by the spring 20, which thereupon returns the swinging frame to normal position to again dispose the roll 22 in working order. One of the 90 arms 18 of the swinging frame is connected by a link 50 with a pivoted lever 51 provided with a trip lug 52 adapted to be engaged by an actuating element to impart swinging motion to the swinging frame, as 95 hereinafter described.

The feed travel of the carriage 32 is effected by means of an endless chain or conveyer 53 passing around sprocket wheels 54 and 55 mounted on shafts 56 and 57 journaled on 100 the frame 2, and which chain is provided with a lug or projection 58 to engage and move the carriage to the outer end of the frame portion 2 and then move out of engagement with and release the carriage for 105 subsequent retraction. When the carriage is moved outwardly as described a cord or cable 59, connected at one end therewith and at its opposite end with a weight 60 movable in a hollow guide upright 61, operates to 110 raise the weight within the upright so that the weight will subsequently retract or return the carriage to normal position, said cord or cable being trained over a suitable guide pulley 62 at the top of the upright and 115 about a guide pulley 63 at or near the base of said upright. The carriage moves outwardly or forwardly while the filling carrier is still being held by the roll 22 and retaining members 24, 25 and 26, so that the thread end 27 is unwound and extended or carried forward by the carriage for engagement with the holder 49. When the carriage reaches the limit of its outward movement and just prior to its release by the projection 120 58, as shown in Fig. 14, a portion of the carriage comes in contact with a stop 64 at the outer end of the frame 2 and is engaged by a hooked latch 65 carried by a longitudinally 125 extending rock shaft 66, by which the car- 130

riage is held at the limit of its outward movement for a definite period during which the thread end 27 is released from the finder finger and transferred to and engaged with 5 the holder 49. The mechanism for effecting this result comprises a rotary thread engaging and winding hook 67 adjustably mounted on a shaft 68 carrying a sprocket wheel 69 driven by a chain 70 from a sprocket 10 wheel 71 on a transmission shaft 72 driven from the shaft 57 by intermeshing beveled gears 73 and 74. The free end of this hook 67 rotates, as shown in Fig. 6, in a path to engage the thread which is clamped in the 15 slotted extension 35 by the finger 29 at a point between the bobbin and clamped end of the thread and to draw out and loop or wind the thread about the holder 49 a plurality of times, this operation being completed 20 at or about the time the bobbin is released and drops into the battery and the end of the thread is released from the slotted extension 35 by a projective movement of the finder finger. This projective movement of 25 the finder finger is effected by means of a pivoted gravity retracted trip member or pusher arm 75 adapted to engage the plunger head 40 and push the finger inwardly, said arm 75 being periodically moved forward and released for retraction by a lug or 30 projection 76 on the shaft 72. The shaft or rod 66 extends longitudinally of the frame 2 beyond the opposite side of the hopper 1 and is provided with an adjustable arm 77 35 adapted to be tripped to release the latch to permit retraction of the carriage at a proper time period, as hereinafter described. The trip arms 7, 46 and 77 are mounted for rotary adjustment about their shafts so that 40 their position for timed actions to an accurate degree may be regulated, while the hooked winder arm 67 extends through a transverse opening in the shaft 68 to vary its effective length and is adapted to be 45 secured in position by a set screw 68a.

The primary drive gearing for actuating the several parts above described consists of a master or main drive gear 78 provided with a continuous series of external gear 50 teeth 79 adapted to mesh with a primary drive gear 80 loosely mounted on a primary drive shaft 81 provided with a pulley 82 or other means for receiving power from any suitable source. The gear 80 is provided 55 with a recess forming a cam surface 83 and a shoulder 84 for co-operation with a clutch pin 85 on the shaft 81 or wheel 82, and also with a sleeve 86 provided with an annular groove 87 to receive a suitable shifting device 88 by means of which the gear may be moved into and out of operative relation to the clutch pin to throw the gearing into and out of action as desired. The 60 shifting device 88 is operable by means of a lever 89 or other means for holding the gear 80 projected so that the pin 85 will engage the shoulder 84 and turn said gear in a clock-wise direction, while any backward or counter-clock-wise movement of the pin will cause said pin to engage the cam surface 83 and push the gear 80 back, thus preventing any rotary motion from being transmitted thereto in a retrograde motion, whereby damage to the machine is prevented. The gear 78 is also provided with an 65 internally toothed flange 90 to successively engage and turn the gears 14 and 23 at fixed intervals and for predetermined periods to move the feed apron forward for a feed action and to turn the supporting roll 22. 70 On the gear 78 is also a gear segment 91 to engage the gear 14 for the purpose of reversing the motion of the feed apron, after the apron has been operated on its feed motion and before the roller gear 23 is revolved, to loosen up the carriers or bobbins contained in the hopper and straighten out any angularly or irregularly arranged bobbins to a proper feeding position, by means of which binding and choking of the bobbins will be further prevented. On the wheel 78 is also a trip pin 92 to 75 periodically engage and operate the trip arm 77 which retracts the latch device 65, and on said wheel 78 is also a segmental trip flange 93 which operates to successively and periodically engage the door trip arm 7 and the finger trip arm 46, all of the working parts with the exception of the elements 75 and 76 being thereby directly operated 80 from the gear 78. The shaft 56 carries a beveled gear 94 meshing with a similar gear 95 on a transmission shaft 96 carrying a gear 97 which meshes with the teeth 79 of the gear 78 and is driven therefrom, whereby motion is communicated to the continuously driven chain 53. A suitable stop or bumper 98 is arranged upon the hopper or frame at a proper point to arrest the motion of the carriage when retracted and in finding position. The finder finger may be formed with a straight toothed surface 99, as shown in the main views of the drawings, or it may be provided with a concaved surface 100 to conform to the contour of a filled 105 bobbin, as shown in Fig. 16.

The operation of the apparatus is as follows. The filled carriers or bobbins having been supplied to the hopper and the main drive 110 gear set into action, assuming that the carriage is at the end of its outward or feed movement of a previous working motion, the trip flange 93 first engages the arm 7 and swings the door 5 open and then the 115 gear 90 engages and turns the pinion 14 for a forward feed motion of the belt 11, whereby the first filler carrier is discharged through the passage 4 and onto the roll 22. At this stage the pin 92 engages and oper- 120

125 130

ates the latch releasing arm 77 and the carriage is retracted and brought into working position, whereupon the flange 93 engages and trips the arm 46 thus throwing the 5 finder finger into working position. The gear 90 now engages the gear 23 and rotates the roll 22 to turn the carrier during the finding action, the trip 7 being released and the door being closed by the action of 10 the spring 9 to prevent the discharge of any other carriers during such finding action. At this time the gear 91 engages and turns the gear 14 to reverse the motion of the feed apron to properly distribute the 15 carriers within the hopper, and as soon as the thread is picked by the finder finger and the latter released and retracted by its spring upon the movement of the flange 93 past the arm 46 the projection 58 engages 20 and moves the carriage forward. When the carriage reaches the limit of its outward movement it is latched and held for a pre-determined period while the extended end of the thread is being released therefrom 25 and wound by the winder arm about the holder 49. When this action ceases the pin 92 reaches and engages the trip 52 and moves the swinging frame rearwardly to retract the roller 22 and release the carrier 30 from which the thread has been unwound, thus allowing said carrier to drop down into the battery, whereupon the parts will be in position for a repetition of the above described operation.

35 An important feature of my invention, so far as the presentation of the bobbin or carrier to the finding finger is concerned, resides in the dropping of the bobbin from the hopper upon the supporting roll 22, which 40 loosely engages the bobbin and gives it rotary motion. It is desirable to stop this rotary motion as soon as the thread is found and engaged by the finder finger, and this is accomplished with my construction by 45 reason of the fact that when the thread end is engaged and held sufficient resistance will be established to hold the bobbin from rotating with its supporting roller, the latter continuing to rotate without affecting the 50 bobbin. Hence the bobbin may be presented in any position in which the free end of the thread may be disposed with relation to the finder finger, and will be turned positively until the thread is engaged and held by the 55 finder finger, whereupon the rotary motion of the bobbin will be arrested, thus preventing undue strain upon or breakage of the thread.

Another important feature of my invention 60 resides in the extension of the found end of the thread from the bobbin in a direction parallel with the axis of the bobbin and beyond the smaller end thereof, whereby the found end of the thread is positioned, without further manipulation, for connection

with a battery head or, as set forth, first with a support and subsequently to a battery head.

From the foregoing description, taken in connection with the drawings, the construction and mode of operation of the invention will be readily understood and it will be seen that a machine is provided for finding and unwinding the threads from the carriers in a reliable and efficient manner, and for 70 extending or leading out the thread in proper position for the subsequent transferring operation, and for holding the threads of the carriers in such position for the convenience of the weaver or for proper presentation to the loom replenishing mechanism, the machine also serving at the same time to feed the carriers to the battery ready for the transferring action; thus obviating the 75 tedious and time losing operations ordinarily carried out by the weaver in finding and extending the free ends of the filler threads and disposing the same in proper 80 leading position. By the use of a machine embodying the present invention the filled 85 carriers may be automatically conveyed to the loom by any suitable type of conveying apparatus and during their period of transit operated upon by the finder and feeder to automatically place the filler carriers in condition to be supplied to the loom to replenish 90 the filling, with a material saving of time and labor and greater convenience over the 95 methods in common use.

I claim:—

1. In a filling end finder for bobbins, a 100 finder finger comprising a blade free at one end and pivotally mounted at its opposite end for movement in a vertical plane, said blade having a longitudinal edge portion to bear upon the bobbin filling for a finding action, and said blade being formed with a slot 105 extending upwardly and forwardly on a curved line from said bearing edge toward its free end and opening at its rear end through said edge and means for rendering said finger operative and inoperative for pivotal motion.

2. In a filling end finder for bobbins, a 110 finder finger comprising a blade free at one end and pivotally mounted at its opposite end for movement in a vertical plane, said blade having a longitudinal bearing edge to 115 rest upon the filling for a finding action, and said blade being provided with a plurality of spaced slots curved upwardly and forwardly from said finding edge and opening at their rear ends through said edge and means for rendering said finger operative and inoperative for pivotal motion.

3. In a filling end finder for bobbins, a 120 finder comprising a finger mounted for yielding vertical motion, said finger consisting of a plate having a longitudinal bearing edge 125 for contact with the filling, and provided 130

with a plurality of slots curved upwardly and forwardly from said bearing edge and opening at their rear ends through said edge, and means for projecting said finger 5 for a yielding finding action and retracting and holding the finger rigidly against yielding motion.

4. In a filling end finder for bobbins, a finder device comprising a holder, a member 10 mounted to reciprocate in said holder, a finder finger pivoted to said member and normally held rigid therewith in the holder, and means for reciprocating said member to project and retract the finger and swing 15 it on its pivot.

5. In a filling end finder for bobbins, a holder, a reciprocating member, a finder finger pivoted to said reciprocating member and normally held by said member in fixed- 20 joint relation, and means for reciprocating said member for joint breaking and fixing 25 actions.

6. In a filling end finder for bobbins, a support, a member mounted to reciprocate 25 in said support, a finder finger pivoted to said member and normally held rigid therewith in said support, means for moving said member and finger in one direction to project and release the finger for a pivotal motion, and means for retracting said member and finger to lock the finger against pivotal motion.

7. In a filling end finder for bobbins, a finder finger, a member to which said finger 35 is pivoted for swinging motion to finding and retracting positions, respectively, and means controlling said member and finger to move the same in different directions whereby to project and release the finger 40 for finding action and to retract and lock the finger in retracted position.

8. In a filling end finder for bobbins, a finder comprising a finger having a thread engaging surface, said finger being arranged 45 to rest by gravity upon the thread in its finding action and having free vertical movement, and controlling means for said finder finger.

9. In a filling end finder for bobbins, a 50 support having a bifurcated extension and a guide passage communicating with the space between the sides of the bifurcation, a plunger movable in said passage, a finder finger pivoted to said plunger and arranged 55 to project and move in the bifurcation, a spring engaging the plunger to hold it retracted with the pivoted portion of the finder within the passage to hold the finder rigid, and means for sliding the plunger 60 forward to move the pivot point forward of the passage to free the finder for pivotal motion.

10. In a filling end finder for bobbins, a support having a guideway, a bifurcated 65 portion in line with the guideway, a plun-

ger movable in said guideway, a finder finger pivoted to said plunger, a spring for holding the plunger retracted with the part of the finger pivoted thereto disposed in said guideway and said finger disposed with- 70 in the bifurcation, means for actuating the plunger to project the finger, one of the walls of the bifurcation forming a surface, co-operating with the finger to clamp and engage thread, the cutter disposed in said 75 bifurcation and secured to the opposite wall thereof.

11. In an apparatus of the character described, the combination with a hopper for containing wound filling carriers or bobbins, a filling end finder, means for relatively moving a wound filling carrier or bobbin and filling end finder in a direction transversely of the longitudinal axis of the carrier or bobbin to enable the finder to find 80 and engage the filling end, and means for moving the filling end finder away from the carrier or bobbin after it has found and engaged the filling.

12. In a filling end finder for bobbins, 90 and in combination with co-operating finding means, a hopper for the bobbins provided with an outlet, a feeder for successively feeding the bobbins to the outlet, dropper mechanism controlling the discharge of bobbins through the outlet, and means for operating the aforesaid parts in timed accord.

13. In a filling end finder for bobbins, and in combination with co-operating finder means, a hopper for the bobbins provided 100 with a discharge outlet, a feeder for successively feeding the bobbins to said outlet, dropper mechanism controlling the outlet, and means for actuating the aforesaid parts, said means being operative to reverse the 105 motion of the feeder between successive feeding operations thereof.

14. In a filling end finder for bobbins, and in combination with co-operating finding means, a hopper for the bobbins provided 110 with a discharge outlet, dropper mechanism controlling said outlet, a feeder for successively moving the bobbins to the outlet, means for operating the aforesaid parts in timed accord, and means within the hopper 115 for maintaining the bobbins in a predetermined position for discharge through the outlet.

15. In a filling end finder for bobbins, and in combination with co-operating finding 120 means, a hopper for the bobbins provided with a discharge outlet, a valve controlling the individual discharge of bobbins through said outlet, a detent for holding each discharge bobbin in proximity to the outlet for a finding action, and means for alternately opening and closing the valve and moving the detent into and out of operative relation.

16. In a filling end finder for bobbins, and in combination with co-operating finding 125

- means, a hopper for the bobbins provided with an outlet, a valve governing said outlet, a feeder for conveying bobbins to the outlet, and a guard roll governing the sides of the outlet for permitting a single bobbin to discharge at a time.
17. In a filling end finder for bobbins, the combination with coöperating finding means, a hopper for the bobbins provided with a discharge outlet, a feeder for conveying the bobbins to the outlet, a valve governing the outlet, and a guard roll arranged to control the sides of the outlet, said roll being yieldingly mounted.
18. In a filling end finder for bobbins, and in combination with coöperating finding means, a hopper having a discharge outlet for the bobbins, means for governing the discharge of the bobbins, a feeder for conveying the bobbins to the outlet, and means for periodically reversing the motion of the feeder.
19. In a filling end finder for bobbins, and in combination with coöperating finding means, a hopper for the bobbins provided with a discharge outlet, a feeder for conveying the bobbins to the outlet, valve mechanism governing the discharge of the bobbins, and operating mechanism for actuating the parts at timed intervals, said mechanism embodying elements arranged to come into action at spaced periods for imparting feed motion to the feeder and then reversing the same.
20. In a filling feeder for bobbins, and the combination with coöperating finding means, a hopper for the bobbins provided with a discharge outlet, a valve governing said outlet, a feeder for feeding the bobbins to the outlet, a detent for holding each bobbin in position for a finding action and simultaneously imparting rotary motion thereto.
21. In a filling finder for bobbins, and in combination with coöperating finding means, a hopper for the bobbins provided with a discharge outlet, means for discharging the bobbins through said outlet, means for centering the bobbins for a finding action, a detent for maintaining the bobbins in position for the finding action and imparting rotary motion thereto, and means for moving said detent into and out of the path of discharge motion of the bobbins.
22. In a filling end finder for bobbins, and in combination with coöperating finding means, a hopper for the bobbins provided with a discharge outlet, a valve controlling said outlet, a rotatable detent for holding each discharged bobbin in position for the finding action and imparting rotary motion thereto, a swinging support for said detent, and means for imparting back-and-forth motion to said support at timed intervals and for rotating said detent.
23. In an apparatus of the character de-
- scribed, the combination with a hopper for containing wound filling carriers or bobbins, a filling end finder, means for relatively moving a wound filling carrier or bobbin and filling end finder in a direction transversely of the longitudinal axis of the carrier or bobbin to enable the finder to find and engage the filling end, means for moving the filling end finder away from the carrier or bobbin after it has found and engaged the filling, and means for securing the filling end beyond the end of the filling carrier or bobbin.
24. In a filling thread finder for bobbins, a finder for finding the end of the thread, means coöperating therewith for extending the found end of the thread, and means for winding the found end of the thread about a support.
25. In a filling thread finder for bobbins, a finder for finding and clamping the end of the thread, means for moving the finder through a course of travel to extend the end of the thread, means for engaging and connecting the end of the thread with a support, and means for releasing the thread from the finder.
26. In a filling thread finder for bobbins, a finder for engaging and holding the end of the thread, means for moving the finder through a course of travel to extend the end of the thread, a rotary element for winding the end of the thread held by the finder about a support, and means for releasing the thread from the finder.
27. In a filling thread finder for bobbins, and in combination with bobbin feeding and rotating means, a carriage, a finder finger mounted upon the carriage, said finger being automatically retracted and adapted for projection to engage the thread and upon retraction to clamp the thread end, means for projecting the finder, means for moving the carriage through a course of travel to extend the end of the thread from the bobbin, means for winding the extended end of the thread about a support, and means for projecting the finger while in thread extending position to release the clamped end of the thread.
28. In a filling thread finder for bobbins, means for finding the thread and extending the same from the bobbin, means for depositing the bobbin into a holder, and means for fixing the end of the extended thread to a support, whereby the same may be held extended.
29. In a filling thread finder for bobbins, means for finding and extending the end of the thread, means for depositing the bobbin in a holder, and means for winding the extended end of the thread about a support.
30. In a filling thread finder for bobbins, means for finding and extending the end of the thread, means for depositing the bobbin

in a holder, and a rotary element for winding the extended end of the thread about a support.

31. In a filling thread finder for bobbins, 5 means for finding and extending the end of the thread, means for depositing the bobbin in a holder, and a rotary member having a hooked portion to engage and wind the end of the thread about a support.

10 32. In a filling thread finder for bobbins, means for finding and extending the end of the thread, means for depositing the bobbin in a holder, means for maintaining the end of the thread in extended condition, means 15 for connecting the thread with a support at a point between the bobbin and the aforesaid means, and means for releasing the thread from said aforesaid means.

10 33. In a filling thread finder for bobbins, 20 a hopper, bobbin feeding and rotating means, a reciprocating carriage, a finder mounted upon the carriage and adapted to be projected and automatically retracted to find and hold the end of the thread, means 25 for dropping the bobbin into a holder, means for moving the carriage in one direction to extend the end of the thread and to hold it clamped in extended condition, means for winding the clamped end of the 30 thread about a support, and means for releasing the thread from the finder and returning the carriage to normal position.

34. In a filling thread finder for bobbins, bobbin feeding and rotating means, a reciprocating carriage, a finder mounted on the carriage to engage, find and clamp the end of the thread, means for projecting the finder at the finding point, means for normally holding the finder retracted, means 40 for moving the carriage at the completion of the finding action to extend the end of the thread, means for locking the carriage at the end of such movement, means for dropping the bobbin from the feeding and 45 rotating means into a support, means for winding the extended end of the thread about a holder, and means for freeing the thread from the finder, and releasing and returning the carriage to normal position.

50 35. In a filling thread finder for bobbins, and in combination with thread finding and extending means, means for holding the thread extended, means for winding the same about a support, and means for releasing the thread from said holding means.

36. In a thread finding mechanism for bobbins, a finder, means for bringing a bobbin in juxtaposed relation to and actuating the finder to find and extend the end of the 60 thread, means for depositing the bobbin upon a support, and means for fixing the extended end of the thread to a holder.

37. In a filling thread finder for bobbins, and in combination with thread finding and 65 extending means, a support, and means for

winding the end of the thread about said support at a point between the bobbin and the finder and releasing the portion of the thread held by the finder from the latter.

38. In a filling thread finder for bobbins, 70 a hopper, means for feeding, rotating and discharging a bobbin, means for finding the thread and extending the same from the bobbin, means for connecting the extended end of the thread with a support and returning the finder to normal position for the succeeding action, and a single rotary driving element provided with portions for operating all of the aforesaid parts in timed accord.

10 39. In a machine of the class described, the combination of a filling end finder for finding and engaging the end of the filling wound upon the carrier or bobbin, means for moving the filling end finder beyond the 85 end of the carrier or bobbin after it has found and engaged the filling end, and means for securing the filling end to a holder or support after it has been moved beyond the carrier or bobbin by the filling end 90 finder.

40. In a filling replenishing loom, the combination of a filling end finder to find and engage the end portion of the filling wound upon a carrier or bobbin and extend it 95 from the wound carrier or bobbin, a hopper or receptacle to receive the wound carrier or bobbin the end of the filling of which has been found and engaged by the filling end finder and position the filling carrier or bobbin for transfer to the shuttle.

41. In a filling end finder for bobbins, a finder for finding and holding the end of the thread, and a support for the bobbin during the finding action comprising a rotary roll, 100 adapted to rotate the bobbin during the finding action of the finder and to allow the bobbin to remain stationary under resistance of the finder as soon as the end of the thread is found and engaged by the finder.

42. In a filling replenishing loom, the combination of a filling end finder to find and engage the end portion of the filling wound upon a carrier or bobbin and extend it from the wound carrier or bobbin, means 115 for securing the end of the extended filling, a hopper or receptacle to receive the wound carrier or bobbin the end of the filling of which has been found and engaged by the filling end finder and position the filling carrier or bobbin for transfer to the shuttle.

43. In a filling end finder for bobbins, a finder for finding the end of the thread, a rotary roll, on which the bobbin rests, for supporting and rotating the bobbin during the finding action, said roll being adapted to turn independent of the bobbin while the latter is held stationary under the resistance of the end of the thread held by the finder, and means for rotating the roll.

44. In a filling end finder for bobbins, in combination with a finding means for engaging and holding the end of the thread, a support for the bobbin during the finding action, said support being operative to rotate the bobbin during the finding action, the bobbin being loosely held in contact with said support, whereby the bobbin will be held against rotation by the resistance of the found end of the thread to obviate breaking of the same.

45. In a filling replenishing loom, the combination of a main hopper to hold the wound filling carriers or bobbins, a receptacle or transfer hopper for receiving the wound filling carriers or bobbins, and a filling end finder between the main and transfer hoppers to find and engage the filling end wound upon a filling carrier or bobbin before it is transferred to the receptacle or transfer hopper.

46. In a filling end finder for bobbins, a finder for finding the end of the thread, a rotary roll for loosely supporting the bobbin during the finding action, means for rotating said roll, a swinging carrier for the roll, and means for swinging said carrier to move the roll out of the path of the bobbin at the conclusion of the finding action.

47. In a machine of the character described, the combination of a main hopper for holding a supply of wound filling carriers or bobbins, means acting automatically upon the cylindrical surface of a wound filling carrier or bobbin to find and engage the end portion of the filling and extend it from the carrier or bobbin, and means acting automatically thereafter to transfer the filling carrier or bobbin to the shuttle.

48. In a filling end finder for bobbins, means for loosely supporting and rotating a bobbin, a finder for engaging and holding the loose end of the thread wound upon the bobbin so as to cause said thread end to unwind in the rotary motion of the bobbin, and means for moving said finder toward and from the surface of the bobbin, said finder having a yielding motion when in contact with the thread upon the bobbin to conform to irregularities in the surface thereof.

49. In a filling thread finder for bobbins, means for loosely rotating a bobbin on its axis in a substantially fixed plane, and a finder for engaging and moving the thread end away from the bobbin and holding the bobbin from rotation by engagement with said threaded end.

50. In a filling thread finder for bobbins,

means for loosely rotating a bobbin on its axis in a substantially fixed plane and a finder adapted to movably engage the surface of the bobbin for engaging and holding the thread end, said finder being movable away from the bobbin at the end of the finding action to carry the thread end from the bobbin and to hold the bobbin through said thread end from rotation.

51. In a machine of the character described, a hopper to hold wound filling carriers or bobbins, a filling end finder, means for causing the filling end finder to act upon the surface of the filling wound upon the carrier or bobbin and find the end of the filling, means for moving the filling end finder away from the carrier or bobbin to extend the end of the filling, and means for securing the end of the extended filling.

52. In a machine of the character described, the combination of a filling end finder, means for delivering a wound filling carrier or bobbin for the action of the finder, means for relatively moving the wound mass of filling on the carrier or bobbin and finder in a direction transversely of the longitudinal axis of the carrier or bobbin to cause the finder to find and engage the filling end, and means for moving the finder to extend the filling from the wound carrier or bobbin after it has been found.

53. A filling finder mechanism, comprising, in combination, a filling end finder, means for causing it to act upon the wound mass of filling on a carrier or bobbin to find and engage the filling end, means for reciprocating the filling end finder to extend the filling end and return to initial position, and means for securing the extended end of the filling.

54. A filling finder mechanism, comprising, in combination, a filling end finder, means for causing it to act upon the wound mass of filling on a carrier or bobbin to find and engage the filling end, means for reciprocating the filling end finder to extend the filling end, means for securing the extended end of the filling at a point beyond the end of the carrier or bobbin, and means for releasing the end of the filling from the finder.

I testimony whereof I affix my signature in presence of two witnesses.

THOMAS CARTER.
